ATTORNEY

UNITED STATES PATENT OFFICE.

FREDERICK ONSLOW BROOKE DENNYS, OF LEXHAM GARDENS, LONDON, ENGLAND.

BALL CARRIER.

Application filed November 7, 1924. Serial No. 748,340.

To all whom it may concern:

Be it known that I, FREDERICK ONSLOW BROOKE DENNYS, a subject of the King of Great Britain and Northern Ireland, residing at 94 Lexham Gardens, W. 8, in the county of London, England, have invented new and useful Improvements in Ball Carriers, of which the following is a specification.

10 This invention relates to carriers for golf balls, tennis balls, and the like, and has for its object to provide for a more convenient method of carrying the balls.

According to the invention the carrier, 15 or pouch as it may be called, comprises in combination a member formed with a plurality of receptacles in spaced relationship and an elastic covering yieldingly disposed thereupon. In the preferred form, this is 20 carried out in practice by means of an endless elastic band disposed or stretched around a perforated plate-like member, as will now be described with reference to the accompanying drawings, in which:—

25 Figure 1 is a view in perspective of a carrier for tennis balls;

Figure 2 is a sectional elevation of the same; and

Figure 3 is a plan view, with a part 30 broken away, of a golf ball pouch.

Referring to Figures 1 and 2, the carrier consists of a more or less rigid plate 1, preferably of 3-ply wood, which is provided with six circular holes of slightly smaller 35 diameter than a tennis ball; a rubber band 2 passing around the plate; and a chain handle 3 secured to the top corners of the plate by means of studs 4.

In operation six tennis balls designated 40 5 are inserted between the plate and band and positioned in the holes as shown in Figure 2. The stretching of the rubber band when the balls are inserted causes the latter to be firmly pressed into their holes 45 and retained securely in position. When there are no balls in the carrier the band may either pass loosely round the plate or be slightly stretched, but in either case the chain 3 will prevent the band slipping off 50 the plate.

This form of carrier is comparatively simple and inexpensive to manufacture; the carrier is light and the balls securely held;

also the balls are substantially protected from soiling and damage from rain and 55 other causes.

The golf ball pouch illustrated in Figure 3 is of a size which will enable it to be readily inserted and carried in the pocket of a golf caddie bag. The plate 1 is preferably of metal such as aluminium, and the rubber band slightly stretched initially so that when there are no balls in the pouch it will be retained in position.

It will be understood that many modifications may be made in the arrangement and construction of the ball carrier or pouch without departure from the scope of the invention.

I claim:—

1. A ball carrier comprising in combination a member formed with a plurality of seats in spaced relationship and an elastic covering yieldingly disposed thereupon and adapted to retain a ball in its seat and to 75 permit its removal therefrom without removal of the covering.

2. A ball carrier comprising in combination a perforated member for receiving and positioning the balls and an elastic bandage 80 for securing the balls in position.

3. A ball carrier comprising in combination a perforated plate-like member and an endless elastic band disposed around said member.

4. A ball carrier comprising in combination a substantially rigid plate provided with holes of smaller diameter than the balls and a band of elastic material stretched thereover.

5. A ball carrier comprising in combination a perforated plate-like member, an endless elastic band disposed around said member, and a handle connected to said member and adapted to prevent separation of said band therefrom.

6. A ball carrier comprising a rigid ball-seating member adapted to receive and seat a plurality of balls and a flexible, self-tensioning cover adapted to contact with said balls and by its inherent elasticity to retain the balls in their respective seats and to permit removal of any ball without removal of the cover.

FREDERICK ONSLOW BROOKE DENNYS.
